Primary Examiner — Catheri Oliver(74) *Attorney, Agent, or Firm* — Carol N. Green, Esq.(57) **CLAIM**

The ornamental design for a pocket handkerchief holder, as shown and described.

DESCRIPTION

FIG. 1 is a front perspective view of the invention.

FIG. 2 is a rear perspective view of the invention.

FIG. 3 is a front view of the invention.

FIG. 4 is a rear view of the invention.

FIG. 5 is a side view of the invention.

FIG. 6 is a top view of the invention; and,

FIG. 7 is a bottom view of the invention.

1 Claim, 3 Drawing Sheets**FIG. 1**

FIG. 2

FIG. 3

FIG. 4

FIG. 5

FIG. 6

FIG. 7
